M. A. FLAUTT

AUTOMOBILE HEADLAMP

Filed Oct. 11, 1924

UNITED STATES PATENT OFFICE.

MELVIN A. FLAUTT, OF WAYNESBORO, PENNSYLVANIA.

AUTOMOBILE HEADLAMP.

Application filed October 11, 1924. Serial No. 742,971.

To all whom it may concern:

Be it known that I, MELVIN A. FLAUTT, a citizen of the United States, residing at Waynesboro, in the county of Franklin and State of Pennsylvania, have invented certain new and useful Improvements in Automobile Headlamps, of which the following is a specification.

The present invention relates to means for controlling or directing the rays of light from the head lamps of automobiles and the like, and the object is to provide a simple structure of this character, preferably in the form of an attachment that can be applied to the standard type of head lamp and will insure the light therefrom being properly directed and the glare eliminated.

In the accompanying drawings:

20 Figure 1 is a horizontal sectional view through the preferred embodiment of the invention,

25 Figure 2 is a rear elevation of the attachment and the glass to which it is applied,

Figure 3 is a detail sectional view taken on the line 3—3 of Figure 2,

30 Figure 4 is a detail perspective view showing the screw mounting for the wall adjusting means.

35 In the embodiment disclosed, a well-known form of lamp is shown and is designated generally by the reference numeral 5. In it is located the usual electric light bulb 6. The glass for the lamp is shown at 7.

40 Crossed supporting arms or bars 8 are provided as a mounting for the light-controlling or directing means. These arms terminate in hooks 9 that are engaged over diametrically opposite edges of the glass 7.

45 Mounted on the arms at their crossing point is a series of walls, one within the other, these walls preferably being formed by a strip that is coiled, the convolutions 10 thereof forming the said walls. The center

50 of the strip is held in place by a bolt 11 that preferably passes through the glass 7, as illustrated in Figure 1. The strip increases in width from its inner to its outer end, so that the walls gradually increase in width as will be evident by reference to Figure 1, and the convolutions are preferably spaced successively farther and farther apart. As a consequence of the increasing

width it will be noted that as the outer edge of the strip rests against the glass the inner edge extending farther and farther from the same forms in the rear end of the light directing means, a recessed seat that receives the front end of the electric lamp 6.

55 The coil is surrounded by an outer wall 12 having diametrically opposite lugs in the form of nuts 13 that are located in openings 14 formed in one of the supporting bars 8. Screws 15, journaled in the said bar, have threaded engagements with 60 said lugs.

65 In the inner sides of the walls are formed openings 16 which are aligned and therefore allow the light from the lamp 6 to pass inwardly and downwardly, the two 70 lamps producing along the road diagonal beams of light as illustrated in Figure 1.

75 Preferably the inner and outer faces of the coil and the inner face of the surrounding wall 12 are bronzed, as a consequence of which the light reflected inwardly from said walls is toned down upon the reflector and is reflected outwardly in the form of a glow which gives splendid illumination but entirely eliminating the glare. The wall 12 is made adjustable so that its rear edge may be placed in or behind the line extending from the filament of the lamp to the inner edge of the bezel or exposed portion of the glass 7. By this adjustment the device can 80 be properly fitted to the particular lamp so that no rays will escape directly from the lamp through the marginal portions of the glass and the entire structure may be made to emit the glareless glow above indicated.

85 From the foregoing, it is thought that the construction, operation and many advantages of the herein described invention will be apparent to those skilled in the art, without further description and it will be understood that various changes in the size, shape, proportion and minor details of construction may be resorted to without departing from the spirit or sacrificing any 90 of the advantages of the invention.

100 What I claim, is:

1. A light shield for head lamps, comprising a series of walls formed by a coiled strip, the convolutions of which are spaced apart, the inner portion of said strip and the inner convolutions formed thereby being 105

narrower than the outer portion and outer convolution, forming a central lamp-receiving recess, and means for mounting the same on a head lamp.

6. A light shield for head lamps, comprising a series of walls formed by a coiled strip, the convolutions of which are spaced apart, said strip gradually increasing in width from its inner to its outer end, forming a central lamp-receiving recess and convolutions that increase in width toward the outer portion of the shield, and said strip having its convolutions increasing in distance apart from its inner to its outer end.
10. 3. A light shield for head lamps comprising a series of walls, one within the other leaving open-ended spaces, the inner of said walls being of less width than the outer, forming a lamp-receiving recess, the outer 20 of said walls having aligned openings therethrough to permit lateral direct rays from a lamp placed in the recess.
15. 4. A light shield for head lamps, comprising a series of walls formed by a coiled strip, the convolutions of which are spaced apart, said strip gradually increasing in width from its inner to its outer end, forming a lamp-receiving recess, said strip having its convolutions increasing in distance

from its inner to its outer end, the outer of 30 said convolutions having aligned openings therethrough to permit lateral direct rays from a lamp placed in the recess.

5. A light shield for head lamps, comprising a series of walls, one within the other, 35 leaving open-ended, light emitting spaces, an outer wall surrounding the said series, and means for adjusting said wall with respect to the series of walls.

6. A light shield for head lamps, comprising a coil forming a series of walls, one within the other, leaving open-ended, light-emitting spaces, an outer wall ring surrounding the coil, and means for adjusting said wall with respect to the series of walls. 40

7. A light shield for head lamps, comprising crossed supporting bars, a strip in the form of a coil located at the juncture of the bars, the strip increasing in width from the inner towards the outer end, a wall ring 50 surrounding the coil, and a screw adjustment means between the wall ring and one of the supporting bars for holding said ring in different positions with respect to the coil. 55

In testimony whereof, I affix my signature.

MELVIN A. FLAUTT.
